UNITED STATES PATENT OFFICE.

JOHN STRASZER, OF MANCHESTER, MISSOURI.

CUT-OFF FOR CISTERNS SUPPLY-PIPES.

SPECIFICATION forming part of Letters Patent No. 233,573, dated October 19, 1880.

Application filed May 6, 1880. (No model.)

To all whom it may concern:

Be it known that I, JOHN STRASZER, of Manchester, in the county of St. Louis and State of Missouri, have invented a new and 5 Improved Cut-Off for Cistern Supply-Pipes, of which the following is a specification.

The object of this invention is to provide a simple and durable device by means of which the rain-water flowing through the rain-water 10 conductors to the cistern may be cut off and made to flow in another direction when the cistern is full.

Figure 1 is a vertical sectional elevation of the device with the shoe closed so as to form 15 a continuous pipe. Fig. 2 is a vertical sectional elevation of the device with the shoe adjusted to intercept the flowing water and conduct it outside of the pipe.

Similar letters of reference indicate corresponding parts.

In the drawings, A represents the upper section of the pipe cut away or scarfed, as shown at *a*, the lower edge of said upper section being crimped or pressed inward, as shown at *b*, so 20 as to leave a little space between said end and lower section of pipe B, into which lower section, B, the upper section, A, enters for a short distance, and the two sections are riveted together at about their longitudinal centers by 25 the rivets C C. The lower section, B, is cut away or scarfed at about half its diameter, as shown at *b*, so that when the two sections A B are connected they present a pipe or conductor having a nearly elliptical front opening, D. The said lower section, B, is also crimped or pressed, as shown at *c*, so as to fit 30 against the upper section, A, and form a tight joint. E is the curved or scoop-shaped shoe,

provided with longitudinal slots *f*, which shoe E is set over the opening D, its slotted edges 40 entering between the sections A B, and is held in place adjustably by the rivets C C, that pass through its slots *f*, so that said shoe E, when closed over the opening D, as shown in Fig. 1, constitutes, in combination with the sections 45 A B, a continuous pipe through which the water may readily flow to the cistern.

When the cistern is full and it is desirable to divert the water elsewhere, the said shoe E is pulled vertically upward the full length of 50 the slots *f* and then drawn forward and downward to the sloping position shown in Fig. 2, and is held in place by the engagement of its ring *g* with the hook or pin *h*, which projects from the front of the lower section, B. The 55 lower or rear end of this shoe E being crimped or pressed, as shown at *m*, enters behind the crimped or pressed end *b* of section A, and thereby forms a tight joint when the said scoop E is in the position shown in Fig. 2. 60

This device is cheap, simple, durable, and easily operated, is not liable to get out of order, and permits a free and unobstructed flow of water to the cistern, when desired.

Having thus described my invention, I claim 65 as new and desire to secure by Letters Patent—

A cut-off constructed substantially as herein shown and described, consisting of scarfed pipe sections A B, the rivet C, and curved shoe E, 70 provided with slots *f*, as set forth.

JOHN STRASZER.
